Primary Examiner — Jennifer Rivard*(74) Attorney, Agent, or Firm* — Myers Wolin, LLC(57) **CLAIM**

The ornamental design for a tweezer with scoop tips, as shown and described.

DESCRIPTION

FIG. 1 is perspective view of an embodiment of a tweezer with scoop tips showing our new design.

FIG. 2 is a perspective view from the opposite side thereof; FIG. 3 is a top plan view thereof, the bottom view being identical;

FIG. 4 is a front elevational view thereof, the rear view being identical;

FIG. 5 is a left side elevational view thereof;

FIG. 6 is a right side elevational view thereof; and, FIG. 7 is a top plan view thereof showing the tweezer with scoop tips in a state of use.

The broken lines illustrate a portion of the tweezer with scoop tips and form no part of the claimed design.

1 Claim, 2 Drawing Sheets(56)
